UNITED STATES PATENT OFFICE.

RALPH M. SHARAF, OF NEW YORK, N. Y., ASSIGNOR TO R. M. SHARAF MACHINE CO.,
OF BOSTON, MASSACHUSETTS, A CORPORATION OF MASSACHUSETTS.

SEWING-MACHINE FEED MECHANISM.

Application filed October 24, 1916, Serial No. 127,323. Renewed July 13, 1922. Serial No. 484,507.

To all whom it may concern:

Be it known that I, RALPH M. SHARAF, a citizen of the United States, and a resident of the borough of the Bronx, in the city and 5 State of New York, have invented a new and Improved Sewing-Machine Feed Mechanism, of which the following is a full, clear, and exact description.

This invention relates to sewing machines 10 and has reference particularly to machines of the two-needle type, but in certain particulars it need not be limited to a two-needle sewing machine.

Among the objects of this invention is to 15 provide a machine in which each needle has associated with it its own independently operable cloth feeding device whereby the cloth may be fed not only in a straight line but laterally in either direction in curved 20 lines.

A further object of the invention is to provide a differential feed for a two-needle sewing machine in which the control of the feeding devices may be accomplished independently 25 of the other operations of the machine and while the machine is running.

The foregoing and other objects of the invention will hereinafter be more fully described and claimed and illustrated in the 30 drawings forming a part of this specification in which like characters of reference indicate corresponding parts in all the views, and in which—

Figure 1 is a front elevation of a conventional form of sewing machine head and operating mechanism to which is applied my novel means for controlling the several independent cloth feeding devices from below the table;

Figure 2 is a perspective view of the needle mechanism and lace operating devices associated therewith;

Figure 3 is a vertical section of the machine head and table substantially on the 45 line 3—3 of Figure 1;

Figure 4 is a partial view of the same with parts in different positions of adjustment;

Figure 5 is a vertical section on the line 50 5—5 of Figure 3;

Figure 6 is a perspective view of the bottom of the machine showing the general arrangement of the adjusting means for the differential cloth feed;

Figure 7 is a longitudinal view, partly in

section, of the concentric cloth feeding rock shafts;

Figure 8 is a perspective view of the throat plate;

Figure 9 is a perspective view of one of 60 the stationary cloth cutting blades carried by said throat plate;

Figure 10 is a side elevation of a part of 65 the cloth feeding mechanism, the parts being in section on the line 10—10 of Figure 11;

Figure 11 is a plan view of the same; and

Figure 12 is a sectional view indicating a detail of the stitch adjusting mechanism substantially on the line 12—12 of Figure 4. 70

Similar reference characters indicate corresponding parts throughout the various figures of the drawing.

This invention is also disclosed in my other application filed herewith, Serial No. 75 127,322, the claims of said application relating to the means for applying lace or other trimmings to fabrics. Said lace applying devices are so constructed as to be used in connection with either a single needle or a multiple needle machine. It follows, therefore, that the several parts of this machine may be made of any suitable materials and the relative sizes and proportions, as well as the various details of construction, may be modified to a considerable extent without departing from the spirit of the invention hereinafter claimed.

By way of illustration, I show at 10 (Figs. 1, 2 and 3) a common form of sewing machine head supported upon a table 11 and having any suitable driving mechanism including a main shaft 12, a driving wheel 13 and a belt 14.

Within or below the bed 15 of the sewing machine is arranged, as usual, the operating mechanism for the bobbins and the cloth feeding devices. These means include a countershaft 16 having cranks 17 adapted to be rotated from the main shaft 12 by connecting rods 18. Operated from the countershaft 16 in the usual manner is a shaft 19 (Fig. 6) having miter gear connections at 20 with the several rotary bobbins 21.

Associated with the several needle mechanisms described below are independently movable feeding bars 22 (Figs. 6, 10 and 11) having toothed cloth engaging dogs 23 movable upwardly through and reciprocating forwardly and rearwardly along spaced 105 110

openings 24 (Fig. 8) in a throat plate 25 secured to the bed of the machine. The front ends of said bars 22 are pivotally connected to short cranks 26 and 26' extending laterally from adjacent the ends of a pair of concentric rock shafts 27 and 28 respectively, the latter being journaled within the former. The feeding bars have their rear ends lifted by means of a rock shaft 22^a operated from 5 the countershaft 16 by means of a fork 22^b and a cam 22^c. An arm 22^d secured to the shaft 22^a is connected to the rear ends of said bars 22 by means of blocks 22^e over which the bars are slidable substantially 10 horizontally under the operation of the main feeding mechanism described below. Adjacent the opposite ends of said shafts are connected other cranks 29 and 29' respectively (Fig. 7) and which extend therefrom 15 in substantially the same direction as the other cranks. The shafts 27 and 28 are adapted to be oscillated or rocked either together or independently of each other whereby by the throw or stroke of the feed bars 22 20 may be the same or different. Any suitable means may be employed to oscillate the rock shafts for the purpose just stated. As a preferred means for accomplishing this result, I connect pivotally to the cranks 29 and 29' 25 a pair of links 30 whose other ends are pivoted to a pair of blocks 31 (Figs. 3, 4 and 12) slidable in slots 32' formed in a peculiar construction of radius bar 32 which is operated from the countershaft 16 by means of 30 an eccentric 33 co-operating with a fork 34 rigidly connected to said radius bar. The fork is supported upon a short rock shaft 35 journaled to the bottom of the bed. The blocks 31 are movable along the slots 32' 35 toward or to the center of oscillation or axis of the shaft 35 and hence they are movable also outwardly or radially therefrom. By adjusting the blocks and the connected links 40 30 outwardly from the axis of the shaft 35, the effective throw of the blocks and links, and consequently the effective oscillation of the rock shafts 27 and 28, are correspondingly increased. It follows, therefore, that 45 the throw of each of the feed bars is dependent upon the adjustment of the respective block 31, or in other words, upon the throw of the radius bar as made effective through the corresponding crank and link 50 connections. The construction and specific operation of these several link and crank connections for the independent feed bars may be carried out in various ways and made, effective differently, but in the embodiment 55 60 of the invention herein set forth, I contemplate that the shafts 27 and 28, when oscillated together at the same speed, will give the maximum rate of speed to both of the feed bars, and then by decreasing the distance of adjustment of the block 31 out-

wardly from the center of the shaft 35 with respect to one of said rock shafts, the throw of the feed bar pertaining thereto will be correspondingly decreased to any desired extent, whereby, while one of the feeding bars 70 causes a retardation of the cloth as to one row of stitches, the other feeding bar continues in operation at its normal or maximum speed.

In order to variably control the position of the independently slidable blocks 31 along the radius bar, I connect to the several links 30 a pair of distance bars 36 which, in this case, are shown extending approximately vertically from said links, and pivotally connected to the pair of cranks 37 and 37'. These cranks are rigidly connected to the ends of a pair of concentric shafts or pivots 80 38 and 38' respectively, and to the other ends of these shafts are connected other cranks 39 and 39' respectively which have independent linked connections at 40 with a pair of slides 41. A double grooved cam plate 42 is journaled upon a bracket 43 beneath the machine bed, the grooves of the plate being indicated at 44 and each having a spiral end 44^a and a concentric end 44^b. The latter end extends substantially through an arc of 90 degrees, as shown, and the spiral end of the groove pertains to an extent of rotation of the cam plate substantially equal to that just indicated for the concentric end. In other words, the cam plate 42 is adapted to be given a maximum rotary movement of about 180°, during one half of 90 which the concentric portion 44^b is effective, and during the other half the cam portion 44^a is effective. The grooves 44 are arranged on opposite sides of the cam plate in reversed order. Each of the slides 41 is guided for movement substantially in right lines by means of pins 45 and slots 46 and is provided at its end opposite its link connection 40 with an antifriction roller 47 lying and operating within one of said grooves 44. Figure 3 shows the cam plate adjusted to its mid or normal position whereby the slides 41 and their link connections with the blocks 31 are arranged together or in parallelism, whereby the maximum throw of both feed bars will result. Upon rotation of the cam plate 42 in either direction from the position just indicated, one of the slides 41 will be drawn by means of the spiral ends 44^a of the groove 44 toward the center or axis 42' of said cam plate. The antifriction roller 47 pertaining to the other slide, however, will follow along the concentric portion 44^b of its groove without disturbing the adjustment of the throw of the feed bar pertaining thereto. From the description above given and with reference to the drawings it will be observed that the feeding dogs 23 are arranged and operated in parallelism as distinguished from in tandem. The feed 100 105 110 115 120 125 130

bars 22 to which the dogs are connected also are operated in parallel and each bar with its dog is adjustable in throw or speed independently of the other, and hence there is a 5 relative adjustment between the two feeding dogs and a relative increase or decrease of the throw of either of them. It is to be noted also that the distance bars 36, which serve as parts of the connections between the 10 cam plate 42 and the links 30 which determine the effective speed or throw of the several feed bars, are adapted to be moved or reciprocated relatively toward and from each other for the purpose of varying the 15 differential movement between the two feeding dogs.

The means for adjusting or rotating the cam plate 42 may be variously controlled, but as herein shown, I form with said plate 20 a series of rack teeth 42^a and meshing therewith is a pinion 48 connected to a shaft 49 (Figs. 1 and 6) journaled in a bracket 50 extending downwardly from the machine bed. The shaft 49 is fitted with a pinion 51 25 shown having indirect engagement with a gear segment 52 journaled upon any suitable stationary bracket 53. The gear segment 52 is adapted to oscillate preferably in a vertical plane at right angles to the plane of the 30 cam plate 42. As a suitable and convenient means for operating the gear segment 52, while the machine is in operation and independently of the driving and stitch forming mechanisms, I provide a yoke 54 extending 35 downwardly from said segment and adapted to be operated by the operator's knee in either direction. When the yoke is moved laterally on its pivot 52' in either direction from the mid or normal position, a corresponding shortening of the stitch will be 40 produced as to one of the independent stitch forming mechanisms as above set forth, and when the yoke 54 is returned to its normal position, both of the feed bars will move together and to the same extent, causing the cloth to be fed in a straight line. In Fig. 2, I have indicated at 56 the two needles carried by the needle bar 55 to which a vertical reciprocating movement is imparted from 45 the main shaft 12 in any well-known approved manner.

Among the special objects or purposes of the differential feed mechanism above described is to enable me to sew lace, insertion, 55 binding or other trimmings upon any part of cloth fabric, using a plurality of stitching devices and operate both of the feeding devices at the same or different speeds according as I will have the auxiliary fabric 60 applied in a straight line or curved either to the right or to the left. Certain of the figures of the drawings show lace applying devices including a special form of presser foot 57 secured to a presser bar 58 and made 65 with a lace guide 59. Figs. 1 and 2 also in-

dicate at 61 a vertically reciprocating bar employed to feed the lace or the like, and Figs. 8 and 9 show at 76 stationary blades for cutting the cloth to which the lace is sewed. The special construction, however, of the lace or auxiliary fabric applying devices constitutes the immediate subject matter of my other application mentioned above, and hence is not claimed herein and need not be further described with particularity.

Having thus described my invention, I claim as new and desire to secure by Letters Patent:

1. In a sewing machine, two stitching mechanisms arranged to produce laterally-spaced seams, individual feeding devices arranged for cooperation with the respective stitching mechanisms, means for operating said feeding devices, and adjustable means operatively connected for modifying the action of both of said feeding devices each relative to the action of the other.

2. In a sewing machine, a plurality of stitching mechanisms, a separate feeding device for each of said mechanisms, and operatively connected means for simultaneously effecting a relative adjustment in the speed of all of said feeding devices.

3. In a sewing machine, a plurality of stitching mechanisms, individual feeding means associated with the individual stitching mechanisms, operatively connected adjustable devices for simultaneously controlling the speed of all of the individual feeding means, and means for adjusting said devices individually.

4. In a two-needle sewing machine, the combination with the driving and several stitching mechanisms for producing parallel rows of stitches, of cloth feeding devices operating independently of each other and associated with the several stitch forming mechanisms respectively, and operatively connected means to vary the speed of either of said feeding devices while the other operates at a uniform speed.

5. In a sewing machine, the combination with the driving and several stitch forming mechanisms for producing parallel rows of stitches simultaneously, of cloth feeding devices associated with the several stitch forming mechanisms respectively, and operating in parallel, and operatively connected means to vary the throw of either of said feeding devices independently of the other.

6. In a sewing machine, the combination with the driving and several stitch forming mechanisms for producing parallel rows of stitches simultaneously, of cloth feeding devices associated with the several stitch forming mechanisms respectively, and operatively connected means to increase or decrease the throw of either of the feeding devices independently of the other while the machine is in operation.

7. In a two-needle sewing machine, the combination with feeding and stitch forming mechanisms including means for forming parallel rows of stitches simultaneously, of cloth feeding devices associated with the respective stitch forming devices and operating in parallel, and means under the control of the operator's knee and independent of the other operating means for decreasing the throw of either feeding device while the other feeding device remains at its normal throw whereby the cloth is caused to be moved in a curve around the feeding device having the shorter throw. 70
- 15 8. In a sewing machine, the combination with the driving and several individual stitch forming mechanisms including means for producing simultaneously parallel rows of stitches, of feeding bars operating independently of each other for the respective individual stitch forming mechanisms, and means to differentially vary the throws of said feeding bars, said means comprising a pair of concentric rock shafts connected to the bars, and operatively connected means between the driving mechanism and said rock shafts to vary the extent of rotation thereof independently of the stitch forming mechanisms. 80
- 20 9. In a sewing machine, the combination with stitch forming mechanism including main and countershafts for producing simultaneously parallel rows of stitches, of differential speed cloth feeding devices for the respective stitch mechanisms, said feeding devices including a pair of concentric rock shafts, means to oscillate said rock shafts from said countershaft, and operatively connected means to vary the throw of said oscillating means upon the several rock shafts relatively to each other. 90
- 25 10. In a sewing machine, the combination with stitch forming mechanisms including main and countershafts and a plurality of needles adapted to form parallel rows of stitches, of differential speed cloth feeding devices for the respective needles, said feeding devices including a pair of concentric rock shafts, cranks connected to the several 100
- 30 concentric shafts, links connected to said cranks, eccentric mechanism between the countershaft and the links, and means to vary the relative positions of the links with respect to the eccentric mechanism while the machine is in operation. 105
- 35 11. In a sewing machine, the combination with driving and stitch forming mechanisms including a plurality of needles adapted to form simultaneously parallel rows of stitches, of a plurality of parallel feed bars associated with the respective stitch forming mechanisms, a plurality of feed dogs connected to said feed bars, one dog being wholly at one side of the other with respect to the line of movement of the cloth, means 110
- 40 to reciprocate said bars simultaneously in the same direction but to varying distances, means operatively connected adapted to control and vary the feed of any of said bars relatively to another, and a lifting member 75
- 45 acting upwardly upon all of said bars. 12. In a differential feed mechanism for a two-needle sewing machine, the combination of a pair of feed bars, a pair of rock shafts mounted to turn about the same axis connected to the several bars to reciprocate them independently of each other, and means to oscillate said rock shafts to varying extents, said last mentioned means including a radius bar, eccentric mechanism to oscillate the radius bar, links extending from the radius bar to the several rock shafts, and means to vary the relative positions of said links along the radius bar. 80
- 50 13. In a differential feed mechanism for a two-needle sewing machine, the combination of a pair of feed bars, a pair of rock shafts connected to the several bars to reciprocate them independently of each other, and means to oscillate said rock shafts to varying extents, said last mentioned means including a pair of cranks connected to the several rock shafts, a pair of links connected to the cranks, eccentric mechanism to reciprocate the links, a pair of distance bars connected to the links, and means to adjust said distance bars relatively in opposite directions to vary the effect of the eccentric mechanism upon the rock shafts. 90
- 55 14. In a differential feed mechanism for a two-needle sewing machine, the combination of a pair of feed bars, a pair of rock shafts connected to the several bars to reciprocate them independently of each other, and means to oscillate said rock shafts to varying extents, said last mentioned means including a pair of links, eccentric mechanism connected through the links to the several rock shafts and having a radius bar 100
- 60 acting upon said links, distance bars to adjust the links along the radius bar, and a double cam plate connected to said distance bars to move them relatively to each other in opposite directions. 105
- 65 15. In a sewing machine, the combination with driving and stitch forming mechanisms, of independently controllable parallel feeding devices operated from said driving mechanism, and means for shortening the throw of one of said feeding devices while the other remains at its normal throw, said controlling means including a cam member having a pair of cam grooves, each of the grooves being concentric at one end and spiral at its other end and the grooves being reversely arranged on the cam member, and connections cooperating between said cam member and the feeding devices. 115
- 70 16. In a sewing machine, a rock shaft pro- 120
- 75 125
- 80 130

vided with a crank, a set of concentric rock shafts whose axis is parallel to that of the first-named rock shaft, and a set of feed bars each of which has at one end a pivotal and 5 longitudinally-sliding connection with said crank, while the other ends of the feed bars have eccentric connections with the respective concentric rock shafts.

17. In a sewing machine, a rocking member, 10 a set of concentric rock shafts whose axis is parallel to that of said rocking member, and a set of feed bars each of which has at one end an eccentric pivotal and longitudinally-sliding connection with said rocking member, while the other ends of the feed 15 bars have eccentric connections with the respective concentric rock shafts.

18. In a sewing machine, a rocking member a set of concentric rock shafts whose 20 axis is parallel to that of said rocking member, and a set of feed bars each of which has at one end an eccentric pivotal and longitudinally-sliding connection with said rocking member, while the other ends of the feed 25 bars have eccentric connections with the respective concentric rock shafts, and means for giving said rock shafts oscillating motions of equal or different extent.

19. In a sewing machine, two stitching 30 mechanisms arranged to produce laterally-spaced seams, individual intermittently-acting feeding devices arranged for cooperation with the respective stitching mechanisms and disposed out of line with respect 35 to the normal direction of feed, said devices being substantially in transverse alignment at the beginning of each feed movement, and actuating means for causing either feeding device to have a greater feeding action than 40 the other feeding device, or both devices to have equal feed actions.

20. In a sewing machine, a fabric support, 45 two needles and means for reciprocating them jointly toward and from said support, a movable feed dog co-operating with one of said needles, and another feed dog co-operating with the other needle, and means operatively connected for imparting to either of said dogs feed movements of equal and 50 different extent relatively to the other.

21. In a sewing machine, two stitching mechanisms disposed out of line with respect 55 to the direction in which the goods travel normally, individual feeding devices likewise disposed out of line with respect to the normal direction of feed, and in cooperative relation to the respective stitching mechanisms, and adjustable means operatively connected for effecting a variable differential movement of both of said feeding devices relatively to each other.

22. In a sewing machine, a fabric support, 60 two needles arranged to reciprocate toward and from said support, a movable feed dog co-operating with one of said needles, an-

other feed dog co-operating with the other needle, and means operatively connected for imparting to said dogs feed movements of equal and different extent relatively to each other.

23. In a sewing machine, two stitching mechanisms disposed out of line with respect to the direction in which the goods travel normally, individual feeding devices likewise disposed out of line with respect to the normal direction of feed, and in cooperative relation to the respective stitching mechanisms, and controlling means common to both of said feeding devices to adjust the feed action of either of said devices relatively to the other, to produce differential movement thereof.

24. In a sewing machine, two stitching mechanisms disposed out of line with respect to the direction in which the goods travel normally, individual feeding devices likewise disposed out of line with respect to the normal direction of feed, and in cooperative relation to the respective stitching mechanisms, and controlling means common to both of said feeding devices for imparting to either of said devices, a feed movement of greater extent than that imparted to the other device.

25. In a sewing machine, stitching mechanism including two needles disposed out of line with respect to the direction in which the goods travels normally, individual feeding devices disposed in line with the respective needles as regards the normal direction of feed, and each in cooperative relation to one of the needles, and controlling means common to both of said feeding devices for effecting a differential movement of either of said feeding devices relatively to the other.

26. In a feeding mechanism for sewing machines, a main driving shaft extending through the head of the machine, a counter-shaft, a plurality of feed dogs, common means for equally and differentially operating said feed dogs, means on said countershaft adapted to operate said last mentioned means, and means extending uprightly through the head of the machine and connecting said counter-shaft to said driving shaft to rotate said counter-shaft from said driving shaft.

27. In a machine, the combination with the driving and several stitch forming mechanisms for producing rows of stitches simultaneously, of cloth feeding devices associated with the several stitch forming devices respectively, and a single operated means adapted to increase and decrease the throw of each of the feeding devices independently of the other while the machine is in operation.

28. In a multiple sewing machine, the combination with feeding and stitch form-

- ing mechanism including means for forming rows of stitches simultaneously, of cloth feeding devices associated with the respective stitch forming devices, and means under 5 the control of the operative's knee and independent of the other operating means for decreasing and increasing the throw of each feeding device while the other feeding device remains at its normal throw.
- 10 29. In a sewing machine, the combination with the driving and several stitch forming mechanisms for producing parallel rows of stitches simultaneously, of cloth feeding devices associated with the several 15 stitch forming devices respectively, and operatively connected means to increase and decrease the throw of any of the feeding devices independent of the other while the machine is in operation.
- 20 30. In a sewing machine, the combination with driving and stitching mechanisms for producing multi-rows of stitches, of feed-

ing means associated with the stitch forming mechanism respectively, and a single means severally controlling the speed of said feeding means. 25

31. In a sewing machine, two stitching mechanisms arranged to produce laterally spaced seams, individual feeding devices arranged for co-operation with the respective stitching mechanisms, means for operating said feeding devices, adjustable means modifying the action of the feeding device, and a single means adapted to increase and decrease the throw of either of the feeding devices independent of the other while the machine is in operation. 30

In testimony, that I claim the foregoing as my invention, I have signed my name in presence of two subscribing witnesses.

RALPH M. SHARAF.
